UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

SAVINGS-BANK.

1,073,847.

Specification of Letters Patent. Patented Sept. 23, 1913.

Application filed March 27, 1912. Serial No. 686,639.

To all whom it may concern:

Be it known that I, CHARLES FISHER, a citizen of the United States, residing at Chicago, in the county of Cook and State of Illinois, have invented a new and useful Improvement in Savings-Banks, of which the following is a specification.

This invention relates particularly to savings banks, which are provided with several coin compartments adapted to keep the coins of different denominations separate from each other to facilitate the counting of the coins when the savings bank is taken to a banking institution for the purpose of effecting a deposit of the savings.

The primary object is to provide a savings bank of the character indicated which is of improved general construction, enabling the device to be manufactured very cheaply and improving the operation.

The invention is illustrated in its preferred embodiment in the accompanying drawings, in which—

Figure 1 represents a vertical longitudinal section of a savings bank constructed in accordance with my improvements; Fig. 2, a horizontal sectional view of the casing, taken as indicated at line 2 of Fig. 1; Fig. 3, a plan view of the interior body or core, which is provided with a series of coin compartments and a bill compartment; Fig. 4, a transverse vertical section taken as indicated at line 4 of Fig. 1; Fig. 5, an end elevational view of the core or body shown in Fig. 3; Fig. 6, a top plan view of the lock-casing, this view showing the key-barrel in section, and the bolts in the lock-easing, and showing, also, by dotted lines the U-shaped spring employed in connection with the bolts; Fig. 7, a plan view of the fillet, or spacing-plate, which is adapted to fit in the lock-case shown in Fig. 6; Fig. 8, a side elevational view of the lock-case; Fig. 9, a broken sectional view similar to Fig. 1, but showing one of the coin slot-guards swung inwardly, as occurs in the operation of inserting a coin; Fig. 10, a perspective view of a slot-guard employed; and Fig. 11, a broken perspective view of one of the spring arms of the guard-carrying plate employed.

In the construction illustrated, A represents a core or body in which the coin receptacles are formed; and B, a casing which

receives the body A and is preferably secured thereto by the improved locking means C.

The body A preferably comprises a base 1 formed of sheet metal; and semi-tubular members 2 which rise from the base and are preferably formed of sheet metal, thus affording the coin chambers 3. The semi-tubular members 2 are open at their outer portions, as indicated at 4, so that the coins may be removed from the chambers by a vertical movement. The members 2 comprise individual stampings, and have their lower ends equipped with clenching-lugs 5 which extend through perforations 6 in the base member 1. The peripheral portion of the base member 1 is turned down to afford a flange 7; and the lugs 5 are clenched beneath the plate 1. A finishing base-plate 8 is fitted within the down-turned flange 7. The members 2 are so grouped as to afford between them a bill chamber 9, access to which is had through a bill-opening 10 extending centrally through the plates 1 and 8. The plate 8 is further secured by a ferrule or eyelet 11 which has at its lower end a flange which bears beneath the plate 8 and which has its upper end spun or struck outwardly over the upper surface of the plate 1, as indicated at 12.

The members 2 are so disposed that their cylindrical surfaces will bear against each other at points 13; and the intermediately located members 2 have mutually bracing curved flanges 14 flanking the openings or slots 4. Thus, the sheet metal members 2 which form the coin-receptacles brace each other and have clenching-lugs secured to the base plate 1, so that in this manner it is feasible to construct from sheet metal a rigid, well-braced core. The semi-tubular members 2 are cut away as indicated at 15, at points corresponding with the coin slots of the casing, to admit the coins to the coin chambers, which are open at their upper ends. The members 2 which form the end coin chambers are provided at their upper ends with extensions 2^a which have slots therethrough, as shown in Fig. 1, to receive the bolts of the lock.

The casing B comprises a top member 16 and a peripheral wall 17 depending therefrom. The core A fits snugly within the cas-

ing, the peripheral, or vertical, wall 17 serving to close the openings 4 of the coin chambers. The peripheral wall of the casing is provided in its upper portion with coin-slots 18, which register with the cut-away parts 15 of the tubular members 2 which form the coin chambers.

Attached to the lower surface of the top member 16 of the casing is a guard-carrying member 19 equipped with the resilient arms 20, 21 which carry the slot-guards 22. The member 19 may comprise a stamping of resilient metal. The outer ends of the arms 20 and 21 are located close to the peripheral wall 17 of the casing; and each resilient arm has its end portion provided with a slot or notch 23 adapted to accommodate the arm 24 of the swinging slot-guard 22. The shank of the arm 24 is bent at its upper end and, equipped with a head 25, thus affording lugs or pivot portions adapted to rest upon the upper surface of the resilient arm 20 or 21, as the case may be, when the arm or shank 24 of the guard is entered in the slot 23. It will be noted from Fig. 1 that the head 25 of the guard is confined between the outer end of the spring arm 21 and the top wall 16 of the casing, while the arm 24 of the slot-guard bears against the vertical wall of the casing, the lower end of the arm 24 guarding the coin-slot 18. It will be noted also that the head 25 forms an obtuse angle with the arm 24, so that the spring arm is bent downwardly, or placed under tension.

When a coin is inserted through the slot 18, the guard swings inwardly to the position shown in Fig. 9, in which operation the spring arm is placed under still greater flexure. The inward swing of the arm 24 is limited by the shoulder 26 at the base of the slot 23, and the casing-wall, as is evident from Fig. 9. Thus, it is impossible to dislodge the slot-guard; and it is evident that after the coin is passed through the slot the guard will resume its normal vertical position, so that coins, once inserted, cannot be removed through the coin slots.

The lock C (not claimed herein) comprises a lock-case 27; bolts 28; a fillet 29; bolt-actuating spring 30; and a key-barrel 31. The lock-case is preferably formed from sheet metal. It comprises a bottom wall 32; up-turned side-flanges 33; up-turned end-flanges 34; and outward extensions 35 carried by the upper portions of the end flanges 34 and having down-turned members 36 separated by spaces 37 from the end walls 34, thus affording room for the extensions or locking members 2^a with which the core 60 of body A is provided. The end walls 34 of the lock-case are provided with slots through which the reduced outer ends of the bolts 28 extend, as is evident from Figs. 1 and 8.

The bolts 28 comprise flat bars or plates

suitably recessed at points 38 to accommodate the key. These bolts rest upon the bottom wall of the lock-case, as appears from Figs. 1 and 6. The up-turned side flanges 33 of the lock-case are equipped centrally at their upper edges with out-turned lugs 39 provided with slots 40.

The fillet 29 is located in the lock-case above the bolts 28. It is provided with a central opening 41 to accommodate the key-barrel. It is also provided with slots or openings 42 in which work the down-turned extremities 43 with which the arms of the U-shaped spring 30 are provided. These extremities enter perforations with which the bolts 28 are provided. The fillet 29 is provided on its upper surface with recesses 44 to accommodate the arms of the spring 30; and the corresponding side flange 33 of the lock-case is provided with recesses 45 through which the arms of the spring extend.

The lock-case, with the bolts, fillet and spring assembled, are disposed beneath the member 19, the upper surface of the fillet 29 contacting with the lower surface of the member 19. The lock-case is secured to the top wall 16 of the casing by means of clinching lugs 46 formed integrally with the top wall 16, extended through the slots 40 of the lugs 39 of the lock-case, and clinched beneath the lugs 39. Thus, the guard-carrying member 19 and the lock are securely fastened to the top wall of the casing. A finished appearance may be given to the top wall of the casing by applying a finish-plate 47 to the upper surface. This plate may serve as a name-plate, if desired, and is preferably secured by rivets 48 which pass through the plate 47, the top wall 16 of the casing, and the end arms 21 of the guard-carrying plate 19. In a savings bank of oval shape, it is desirable to secure the arms 21 by rivets as shown, so that the free or resilient portions of the arms will not be of too great length, and hence too weak.

The manner of using the improved safe will be readily understood. The core may be inserted in the casing and locked thereto, a key being employed to retract the locking-bolts against the force of their spring, after which the bolts will enter the recesses in the locking members 2^a when the bolts are released from the action of the key. Coins may be deposited in the coin chambers by inserting them through the coin-slots 18, whence they fall, in superposed relation, into the coin-chambers. In the operation of inserting a coin, the slot-guard 22 is turned to the position shown in Fig. 9; and after the coin has been entered, the slot-guard returns to the normal position shown in Fig. 1.

From the description given, it is evident that I have provided an exceedingly simple,

cheap and durable construction, which is nevertheless perfectly adapted to its purpose.

The foregoing detailed description has been given for clearness of understanding only, and no undue limitations should be understood therefrom, but the appended claims should be construed as broadly as permissible in view of the prior art.

10 What I regard as new, and desire to secure by Letters Patent is—

1. In a savings bank, the combination with a casing having a peripheral wall provided with a coin-admission slot, of a resilient slot-guard holder, and a slot-guard carried thereby and having a pivot-portion adapted to effect flexing thereof when the slot-guard is swung about its pivot.

2. In a savings bank, the combination with a casing having a top wall and having also a peripheral wall provided with a coin-admission slot, of a resilient arm adjacent said top wall and projecting near the peripheral wall, and a swinging slot-guard having a pivot-portion confined between said resilient arm and said top wall, and adapted to flex said arm when the slot-guard is swung about its pivot-portion.

3. In a savings bank, the combination with a casing having a peripheral wall provided with a coin-admission slot, of a resilient arm having its end provided with a slot, and a slot-guard having an arm extending through said second-named slot, and having a head disposed above said resilient arm.

4. In a savings bank, the combination with a casing having a top wall and having also a peripheral wall provided with a coin-admission slot, of a resilient arm disposed beneath said top wall and having its extremity provided with a slot, and a slot-guard extending through said last-named slot and having a head confined between said top wall and said resilient arm.

5. In a savings bank, the combination with a casing having a top wall and having also a peripheral wall provided with a coin-admission slot, of a bent slot-guard having a head-portion forming an angle with its body portion, and a resilient arm between which and said top wall said head portion is normally confined, said head-portion being adapted to flex said resilient arm when the slot-guard is swung in the operation of inserting a coin.

6. In a savings bank, the combination with a casing having a top wall and having also a peripheral wall provided with a plurality of coin-admission slots, of a guard-carrying member secured to the lower surface of said top wall and equipped with a plurality of resilient arms, and a plurality of slot-guards carried by the free end-portions of said arms and adapted to turn with relation thereto and effect flexing of said resilient arms.

7. In a savings bank, the combination with a casing having a top wall and having also a peripheral wall provided with a plurality of coin-admission slots, of a guard-carrying member secured to the lower surface of said top wall and equipped with a plurality of resilient arms having their extremities provided with notches, and angular slot-guards engaging said notches and adapted to flex the resilient arms when swung inwardly by the coins.

8. In a savings bank, the combination with a casing having a peripheral wall provided with a coin-admission slot, of a resilient guard-holder, and a slot-guard suspended from the extremity of said resilient guard-holder and adapted to flex the guard-holder when the slot-guard is swung inwardly.

CHARLES FISHER.
